UNITED STATES PATENT OFFICE.

SAMUEL C. WILSON, OF CHICAGO, ILLINOIS.

FLAG.

1,303,623.

Specification of Letters Patent. Patented May 13, 1919.

Application filed July 20, 1917. Serial No. 181,781.

To all whom it may concern:

Be it known that I, SAMUEL C. WILSON, a citizen of the United States, and a resident of the city of Chicago, in the county of Cook and State of Illinois, have invented certain new and useful Improvements in Flags; and I do hereby declare that the following is a full, clear, and exact description of the same, reference being had to the accompanying drawings, and the numerals of reference marked thereon, which form a part of this specification.

This invention relates to improvements in a flag.

Flags as heretofore constructed have been exceedingly flimsy, and when unfurled, the wind, especially a strong wind, causes the flag to snap and whip until the same starts to shred or tear at the outer end, which tearing continues until the flag is completely destroyed or rendered unsightly. The fabric of the flag so destroyed is perfectly good and were the flag not torn in shreds, would last a long time, perhaps several years.

It is a very frequent happening to hoist a new flag which, at the end of a week or so, is completely destroyed. This entails considerable expense in continuously replacing flags and as well results in the destruction of considerable material for which a reasonable amount of service has not been secured.

It is an object of this invention to provide a flag and reinforcement therefor which will absolutely prohibit the flag whipping itself to pieces, and in which the flag will last until the fabric of which it is composed wears out.

It is further an object of this invention to provide a reinforced flag which consists of reinforcements at and along the outer edge, and in which the flag is reinforced for the entire length thereof so that a tear or hole in one part will be confined locally and cannot spread by the waving and whipping of the flag in a strong breeze.

It is further an object of this invention to provide a flag in which the reinforcement is accomplished in a very simple manner, thereby not making the cost of flags excessive, and in which the premature destruction of the flag by the elements is almost impossible.

The invention (in a preferred form) is illustrated in the drawings and hereinafter more fully described.

On the drawings:

Figure 1 is a front elevation of a flag embodying my invention.

Fig. 2 is a longitudinal section showing one manner of reinforcing the outer edge. 60

Fig. 3 is a longitudinal section showing another method of reinforcing the edge.

Fig. 4 is a view of a flag illustrating another method of reinforcement.

Fig. 5 is a fragmentary view illustrating 65 another method of reinforcement.

Fig. 6 is a view of a flag showing a further method of reinforcement.

Fig. 7 is an enlarged fragmentary detail illustrating another method of constructing 70 a flag.

As shown in the drawings:

The flag is shown as the United States flag, and comprises a plain field 1, in which the stars 2, are inserted. The stripes 3, are constructed of ribbons or strips of suitable colored flag material, and are sewed together along their edges 4, as is usual. The outer edge 5, of the flag, as shown in Fig. 2, is folded back upon itself and firmly secured by several rows of transverse stitching 6. A plurality of rows of successive transverse stitchings 7, are provided from the outer end entirely across the body of the flag. Successive rows of longitudinal stitching 8, 85 are also provided from the bottom to the top of the flag. Each row of stitching is independent of the others, and a rent made at one point is thereby locally confined.

In the construction shown in Fig. 3, a cord 9, is secured at the outer edge of the flag and the outer edge 10, of the fabric, is folded thereover and firmly sewed to the main body of the flag providing a strong corded edge. 95

In the construction shown in Figs. 4 to 6, inclusive, the reinforcing sewings or stitchings are differently arranged. In Fig. 4, the rows of reinforcing stitches 11, intersect each other diagonally, forming diamond shaped sections. In Fig. 5, the rows of stitches 12, are zig-zagged, and in Fig. 6, the stitches 13, are effected in circular lines and a reinforcing bead is provided at the outer edge. In Fig. 7, the strips 15, are cut 105 on the bias so that the warp and the woof of the strip is directed at an angle or diagonally with the length and width of the flag.

The reinforcing bead at the outer edge or the reinforced turned edge prevents the flag 110

- from whipping or fraying the edge to start longitudinal slits. The flag therefore will not whip itself to pieces in a short time. The many rows of intermediate reinforcing 5 stitches are such that if the flag is pierced at any point, that the said stitches prevent the tear from spreading and confine the tear so that the entire flag is not thereby destroyed by the continual action of the flag.
- 10 The flag may be provided with the rows of stitches or sewing in any desired manner, and I do not desire to limit myself to the particular reinforcement shown, but desire to claim broadly any method of arranging 15 the stitches. The flag may also be corded around the entire circumference thereof, if desired.

By the construction shown in Fig. 7 owing to the diagonal warp and woof of the fabric, 20 the tendency of the flag to whip itself into starting a tear is largely prevented, and a much stronger flag is provided than has heretofore been the case.

Many details of the arrangement of the reinforcement may be varied and numerous 25 changes may be made without departing from the principles of this invention. I therefore do not purpose limiting this application for patent otherwise than necessary 30 situated by the prior art.

I claim as my invention:

1. A flag comprising a plurality of strips sewed together, a reinforcing cord secured in the outer edge of the flag, and rows of 35 reinforcing stitches in the body of the flag.
2. A flag having rows of reinforcing stitches sewed into the body of the flag, and a cord embedded in the outer edge of the flag.
- 40 3. The combination with a flag, of a plurality of rows of stitches in the body of the flag independent of the stitches used to sew the elements together, said rows of stitches

adapted to reinforce the flag, and reduce the whipping effect at the edges of the flag. 45

4. In a flag, the combination of supporting means at one end thereof for mounting the flag so as to wave, and reinforcing means in the body of the flag consisting of independent lines of stitches extending on the 50 bias to the material of the flag and adapted to prevent fraying and tearing of the flag.

5. In a flag, the combination of supporting means along one end thereof for mounting the flag so as to wave, and reinforcing means in the body of the flag consisting solely of a plurality of closely arranged intersecting lines of stitches extending transversely and longitudinally across the flag and engaging the opposite faces thereof 55 so as to prevent fraying and tearing of the flag.

6. In a flag, the combination of supporting means along one edge for mounting the flag so as to wave, reinforcing means along the opposite edge of the flag, and a plurality of closely arranged intersecting lines of stitches sewed through the reinforcing means and extending inwardly therefrom toward the supported end of the flag to prevent tearing and fraying of the reinforced 70 end of the flag.

7. In a flag, the combination of a section of fabric having supporting means along one edge on the bias to the fabric, and intersecting lines of stitches arranged on the bias to the fabric and terminating at the free edges of the flag and adapted to prevent tearing and fraying of the edges of the flag. 75

In testimony whereof I have hereunto 80 subscribed my name in the presence of two subscribing witnesses.

SAMUEL C. WILSON.
